FOLDING MACHINE

Christian Christiansen, Swampscott, Mass., assignor to Rotary Machine Company, Inc., Lynn, Mass., a corporation of Massachusetts

Application May 25, 1945, Serial No. 595,815

4 Claims. (Cl. 12—17)

The present invention relates to rotary folding and pressing machines for folding a cemented binding or galloon around the edge of a piece of material such as an insole to which it has been previously stitched and then pressing the binding firmly against the opposite side of the material to cause the binding to adhere to the material. In describing the invention it is convenient to refer to the piece of material to which the binding is to be applied as an insole since the machine is particularly intended for binding insoles. It will be understood that cement is applied first to one face or to a portion of one face of the binding and allowed to dry, before the binding is stitched around the edge of the insole. The insole with the binding attached is then passed through the machine which progressively folds and stretches the binding around the edge of the insole bringing it into contact with the opposite side of the insole and pressing it firmly into position.

The machine embodying the present invention is an improvement on the rotary folding machine shown in the patent to Ridderstrom No. 1,743,286, January 14, 1930. The Ridderstrom machine was intended primarily to operate on relatively thin soft stock, such as binding stitched to the edges of the vamps of women's shoes, while the machine embodying the present invention is particularly adapted to bind the edges of relatively thick, stiff pieces of stock, such as innersoles.

The general construction is the same as that shown in the Ridderstrom patent to which reference may be had for detailed information. The improvement forming the subject matter of the present application has to do with feeding mechanism which will not only turn the binding around the relatively thick edge of an innersole but will also stretch it tight and press it against the edge of the innersole as well as against the top and bottom surfaces.

In the drawings:

Fig. 1 is a side elevation of the machine, certain parts being shown in section.

Fig. 2 is a section on line 2—2 of Fig. 1.

Fig. 3 shows side elevations of the feed wheel and the wiper wheel.

Fig. 4 is a fragmentary side elevation partly in section illustrating the work supporting and guiding mechanism, the folding mechanism, the edge turning device, and the feeding and wiper rolls.

Fig. 5 is a fragmentary sectional plan view taken on a curve corresponding to the circumference of the rotary head.

Fig. 6 is an elevation, partly in section, showing the driving means for the feeding and folding mechanism of the rotary head.

The working elements of the machine consist essentially of a rotary head 38 on which is mounted a series of notched or somewhat crescent shaped feeding and pressing disks 40 which are given a planetary motion as the head rotates, a stationary conical presser point 12 which is ordinarily heated, an edge turning member 79, a feed wheel 74 and a wiper wheel 11. The crescent shaped binding and pressing disks 40 are given their rotative motion by pinions 41 fixed at the inner ends of the shafts 39. The series of pinions mesh with an internal gear ring 42 carried by a sleeve 43 which is fixed in a bearing head and bushing 44 secured to the overhanging arm 45. The shafts 39 are alternately longer and shorter so as to permit a nesting of the pinions 41 in step formation as shown in Fig. 5. The mechanism and operation are more fully described in said patent to Ridderstrom No. 1,743,286. The stationary presser member 12 is mounted on a bracket 91 which is carried by a rock shaft 89 which is journalled in the frame of the machine. A spring 114 holds the conical presser point 12 yielding against the work. The rock shaft 89 is also slidably mounted in said frame for longitudinal motion therein. For the purpose of imparting longitudinal motion to the shaft 89 the inner end of said shaft is engaged by a cam 106 which is actuated by the treadle 54 against the tension of a spring 55. A spring 108 surrounding the shaft 89 is adapted to return said shaft to its normal inoperative position. The presser point is heated by an electrical heating unit 13. The feed wheel, wiper wheel and edge turning member are mounted on a bracket 19 carried by a sleeve 47 which is partially rotated by downward motion of the treadle 54. The spring 55, previously referred to, tends normally to urge the bracket 19, the feed wheel 74, wiper wheel 11 and edge turning member 79 towards the presser point 12 and the pressing disks 40. For insertion of the work the bracket 19 and the parts carried thereby may be depressed by means of treadle 54, which at the same time shifts the presser point 12 away from the edge turning member 79. The function of the heating and pressing point 12 is to soften the cement slightly and to hold the work firmly down on the feed wheel 74.

The rotary head 38 secured to a shaft 46 is driven by the shaft 27 acting through the spiral gears 26 and 25. Below the main shaft 27 is a shaft 66 which is driven from the main shaft by

the worm 63 which meshes with a worm gear 62 (see Fig. 2) on a cross shaft 61. On this cross shaft 61 is a spiral gear 64 meshing with a spiral gear 65 on the shaft 66. At the front end of the shaft 66 is a member 14 at a slight angle to the shaft 66 which acts as a universal joint between the shaft 66 and the hub of a spur gear 16 which is driven thereby. This spur gear 16 meshes with a bevelled gear 17 on a shaft 18 journalled in the supporting bracket 19. Fast on the shaft 18 is a gear 20 which meshes with a smaller gear 21 rotatably mounted on a fixed shaft 22 also in the bracket 19. Another gear 23 of larger diameter than the gear 21 is secured to the gear 21 and itself meshes with the gear 24 forming the hub of the wiper wheel 11 which is rotatably mounted on the shaft 18. The arrangement of the gearing is such that the rotation of the shaft 18 turns the wiper wheel 11 in the same direction as that of the feed wheel 14 but at a speed two and one-fourth times that of the feed wheel 14. The feed wheel 14 (see Fig. 3) is grooved to provide inclined teeth or ribs *a* which, as viewed in Fig. 3, slant downwardly toward the wiper wheel. The wiper wheel has a bevelled face which is also grooved to provide ribs *b* as shown in Fig. 3. These ribs also slant as is shown in Fig. 3. It will be seen that the feed wheel has a working surface formed by ribs which slope so that the trailing ends of the ribs are towards the edge of the work, i. e., towards the wiper wheel, while the wiper wheel has a bevelled working surface at an angle to the working surface of the feed wheel and that the ribs which form the surface of the wiper wheel slope so that the leading ends are at the smaller diameter of the bevelled surface and the trailing ends are at the larger diameter.

The operation of my machine is as follows: The binding or galloon 38 having been provided with a cemented area 33 along the edge of the face which is to be folded into contact with the upper side of the insole S is stitched as shown at 31 to the edge of the insole. The insole is placed in the machine after the bracket 19, carrying the feed wheel 14 and wiper wheel 11, has been swung downwardly and the presser point 12 has been shifted away from the edge turning member 79 by depressing the treadle 54. The operator inserts the insole by pushing it sidewise, i. e., to the right in Fig. 1, to bring the edge of the binding firmly against the edge turning member 79. The presser point 12 and the bracket 19 are then released so that they come into working position. The presser point then presses down on the upper surface of the insole while the feed wheel 14 and wiper wheel 11 press the insole strongly in the direction of the rotary head which is unyieldingly supported. The machine is then started by depressing the treadle 32 and the feed wheel 14 and wiper wheel 11 combined with the action of the disks 40 feed the insole forwardly past the edge turning member 79. The ribs or teeth *a* on the feed wheel

14 tend to crowd the insole toward the wiper wheel 11. The wiper wheel 11 which has a greater surface speed than that of the feed wheel 14 tends to stretch the binding tightly around the edge of the insole and press it firmly against it. As the binding passes the heated presser point 12 the cement is softened slightly so that when the edge of the binding passes under the notched presser disks 40 it is soft and adheres readily to the surface of the insole. The action of the rotary notched presser disks is exactly the same as is described in the Ridderstrom patent already referred to and, therefore, need not be described in detail here.

In actual operation the binding will be found to be stretched tightly around the edge of the insole and secured firmly and smoothly to the upper surface of the insole.

I claim:

- 20 1. In a rotary folding machine of the type having a rotating head, notched feeding and pressing disks mounted for planetary rotation thereon, a presser point and an edge turning member, the combination of a feed wheel engaging the side of the work opposite to the pressing disks and a wiper wheel engaging the edge of the work.
- 25 2. In a rotary folding machine of the type having a rotating head, notched feeding and pressing disks mounted for planetary rotation thereon, a presser point and an edge turning member, the combination of a feed wheel engaging the side of the work opposite to the pressing disks and a wiper wheel engaging the edge of the work, said wiper wheel having a beveled surface provided with inclined ribs.
- 30 3. In a rotary folding machine of the type having a rotating head, notched feeding and pressing disks mounted for planetary rotation thereon, a presser point and an edge turning member, the combination of a positively driven feed wheel 35 engaging the side of the work opposite to the pressing disks and a positively driven wiper wheel engaging the edge of the work, said wiper wheel being driven in the same direction as the feed wheel and at a great surface speed.
- 35 4. In a rotary folding machine of the type having a rotating head, notched feeding and pressing disks mounted for planetary rotation thereon, a presser point and an edge turning member, the combination of a feed wheel engaging the side of the work opposite to the pressing disks, a feed wheel having a working surface formed by ribs inclined so that the trailing ends of the ribs are toward the edge of the work and a wiper wheel 40 having a beveled working surface whose smaller diameter is adjacent the feed wheel, said surface being formed by ribs which are inclined so that the leading ends are at the smaller diameter and the trailing ends are at the larger diameter of the bevel.
- 45 5. In a rotary folding machine of the type having a rotating head, notched feeding and pressing disks mounted for planetary rotation thereon, a presser point and an edge turning member, the combination of a feed wheel engaging the side of the work opposite to the pressing disks, a feed wheel having a working surface formed by ribs inclined so that the trailing ends of the ribs are toward the edge of the work and a wiper wheel 50 having a beveled working surface whose smaller diameter is adjacent the feed wheel, said surface being formed by ribs which are inclined so that the leading ends are at the smaller diameter and the trailing ends are at the larger diameter of the bevel.
- 55 60 CHRISTIAN CHRISTIANSEN.
